UNITED STATES PATENT OFFICE.

JACOB T. JOHNSON, OF ALTANTA, GEORGIA.

DUPLEX FAUCET.

1,392,167.

Specification of Letters Patent. Patented Sept. 27, 1921.

Application filed December 27, 1920. Serial No. 433,320.

To all whom it may concern:

Be it known that I, JACOB T. JOHNSON, a citizen of the United States, residing at Atlanta, in the county of Fulton and State of Georgia, have invented certain new and useful Improvements in Duplex Faucets, of which the following is a specification, reference being had therein to the accompanying drawing.

10 The present invention relates generally to valves and more particularly to faucets, such as used for the delivery of hot and cold water in wash basins, and the like.

The present invention has for its object 15 the provision of a novel and useful double faucet for use in connection with a combination faucet, such as disclosed in my Patent No. 1,336,236, granted April 6, 1920, or which can be attached to any ordinary combination or bath tub faucet, and which is so constructed and operable that the water can either be directed from the main or primary faucet into the basin or other receptacle, or, on the other hand, into a hose of 20 a spray device, or the like.

The present device is more especially useful in barber shops, to provide a compact and convenient controlling device for the hot and cold water, whereby the water can 25 be directed either into the basin or into the hose at the will of the attendant, thereby eliminating the fixtures now generally used in barber and shampoo shops and the like, and providing for economy and a saving in 30 time and trouble.

Another object is the provision of novel 35 and improved duplex secondary faucet for attachment to or use with a main faucet, preferably a combination hot and cold water faucet, whereby by the simple movement of a handle, the water can be diverted in either direction desired, and the construction being simple, compact and comparatively inexpensive, as well as dispensing with the use 40 of several independent fixtures as generally used.

A further object is the provision of such 45 a faucet comprising a novel construction and assemblage of the component elements whereby the device is especially suited for the purposes for which the device is intended and to provide such a device which will be thoroughly convenient and practical.

With the foregoing and other objects in 50 view, which will be apparent as the descrip-

tion proceeds, the invention resides in the construction and arrangement of parts hereinafter described and claimed, it being understood that changes can be made within the scope of what is claimed without departing from the spirit of the invention.

The invention is illustrated in the accompanying drawings, wherein:

Figure 1 is a plan view of the main and 65 secondary faucets.

Fig. 2 is a vertical median section on the line 2—2 of Fig. 1, portions being shown in elevation.

Fig. 3 is a cross-section on the line 3—3 of Fig. 2.

Fig. 4 is a detail view to illustrate the means for limiting the turning movement of the spigot valve.

Fig. 5 is a vertical median section illustrating a modified form of double faucet.

As shown in the drawings, the double faucet is attached to a combination hot and cold water faucet of the type disclosed in my patent above referred to, although it will be understood that the improved device 80 can be used upon other combination or bath tub faucets with equal propriety and success. The combination faucet illustrated is fully described in said patent, but briefly described it comprises a vertical casing or 85 body 11 to which the hot or cold water connections 12 and 13 extend and the casing 11 has a discharge nozzle 14 at the lower end over which the valve 15 is seatable to shut off the flow of both hot and cold water and 90 other valve means are used (not shown) for controlling the flow of hot and cold water as desired, such valve means having a stem 16 projecting upwardly from the casing and bearing a suitable handle 17 where- 95 by the flow can not only be established and cut off, but the supply of hot and cold water also regulated to obtain or draw water of the desired temperature between the two extremes as limits.

The double faucet, which can be conveniently attached to a main faucet of any suitable type, comprises an elongated body 20, which is disposed in a horizontal position, as shown, underneath the main faucet, and 105 which is provided with an upstanding boss 21 between its ends adapted to be screw-threaded onto the nozzle 14 of the main faucet, although other means for attachment can be used. The boss 21 has an 110

inlet recess 22 to register with the outlet of the main faucet, in order that the water can flow from the nozzle 14 into the duplex faucet. The body 20 is formed underneath 5 the same at the forward end with a water discharge spout or nozzle 23 extending forwardly and curved downwardly, to direct the water into the basin or other receptacle, and a hose-attaching nipple 24 is screw-10 threaded into the body 20, or otherwise attached thereto, at a suitable point. As shown, such nipple is attached to the top of the body in rear of the boss 21, and projects upwardly in rear of the main faucet 15 casing 11, for the connection of a shampoo or spray hose, which can remain permanently on said nipple. The nipple 24 being in back of the main faucet, will be out of the way, but still conveniently accessible for the 20 connection of the hose, and the body 20 will occupy very little space underneath the main faucet, so as to not be cumbersome or unsightly.

In order to divert the water from the 25 nozzle 14 to either the discharge spout or nozzle 23 or the hose nipple 24 a valve is provided within the body. For this purpose, said body has a longitudinal bore 25 extending from its forward end to a point 30 rearwardly slightly beyond the nipple 24, and a bushing 26 is fitted in said bore, and said bore and bushing are preferably tapered rearwardly with their larger ends at the forward end of the body 20. The forward end portion of the bushing is secured 35 to the body, such as by means of screw-threads 27. The bushing 26 has ports or openings 28 and 29 at the top opening into the recess 22 to communicate with the discharge nozzle 14 of the main faucet and said bushing has a similar port 30 in the bottom thereof opposite to the port 28 to which the passage 31 of the nozzle or spout 23 leads. The bushing also has the port or 40 opening 32 at the top thereof registering with the nipple 24.

A spigot valve 33 is fitted for rotation in the bushing 26, and is also of similar tapered form, being provided at its forward 45 end with an outstanding stem 34 having a suitable handle 35 thereon for conveniently turning the valve.

A gland nut 36 is fitted on the stem 34 and is screw-threaded into the larger end of the bushing 26 to push the valve 33 snugly 50 into place and retain the same within the bushing. Wear can be taken up from time to time by screwing the nut 36 farther into the bushing as needed, and, if desired, the rear smaller end of the valve can have a tip 55 37 fitted in the recess 37a at the smaller rear end of the bore 25 of the member 20. The valve 33 has a diametrical passage 38 therethrough to register with the ports 28 and 30 60 simultaneously, for establishing the flow of

water from the nozzle 14 to and through the spout or nozzle 23. The valve 33 also has a longitudinal channel 39 to register simultaneously with the ports 29 and 32 for establishing the flow of water from the nozzle 14 to and through the nipple 24, but said passage 38 and channel 39 are so arranged that they register alternately with the respective ports of the bushing by the oscillatory motion of the valve. 75

The turning movement of the valve 33 is limited to bring the passage and channel into registration with the ports conveniently. Thus, said valve has a stop lug 40 extending to one side near the forward end thereof to 80 work in the tail of a bayonet slot 41 provided in the forward end portion of the bushing, as seen in Fig. 4, whereby to limit the turning movement of the valve 33. Furthermore, by turning the valve to one 85 position, and unscrewing the nut 36, the valve can be withdrawn from the bushing, the lug 40 passing through the mouth of the slot 41 which extends longitudinally of the bushing, while the tail of the slot extends 90 transversely.

The use of the secondary or double faucet will be apparent from the foregoing, but briefly stated is as follows: By turning the handle 35 to one extreme limit, the passage 38 registers with the ports 28 and 30 for the flow of water from the main faucet through the nozzle or spout 23, whereas when the handle 35 is turned to the opposite extreme, then the channel 39 will register with the ports 29 and 32 for the flow of water through the nipple 24 and the hose (not shown) fitted on said nipple, such as for use when shampooing or the like. When the handle 35 is turned to an intermediate 105 position, the flow through the ports 28 and 29 is shut off, thereby shutting off the flow through both the nozzle 23 and nipple 24. The main faucet is operated in the usual manner for obtaining either of the extremes 110 of hot and cold water, or water of any desired intermediate temperature. It is preferable to usually leave the valve 33 in a position so that the water will flow through the spout of nozzle 23, whereby it is only 115 necessary to change the position of the valve 33 when using the hose.

A modified or simplified construction is shown in Fig. 5, wherein the body 20' has the hole 22' in the boss 21' for the alternate 120 registration of the passage 38' of the valve 33' and the longitudinal channel 39' of said valve. Such channel is formed by flattening one side of the valve, and the valve 33' is fitted in the bore 25', no bushing being used, 125 and the gland nut 36 screws into the body 20' at the forward end of the bore. When the valve 33' is turned to one position, the passage 38' registers with the opening 22' and passage 31 for the flow of water 130

through the spout or nozzle 23, and when the valve is turned to the opposite position, then the channel or cut-away portion 39' establishes communication between the opening 5 22' and nipple 24'. This construction is more simple and therefore cheaper. The use of the bushing, however, is of advantage in the preferred form, because such bushing can be removed and renewed.

10 Having thus described the invention, what is claimed as new is:—

15 1. A duplex faucet comprising a horizontal body to be disposed below another faucet and having an upper inlet portion between its ends attachable to such other faucet, the body having a delivery spout leading downwardly from between its ends and a nipple extending upwardly from the body at a point spaced longitudinally from said inlet 20 portion and spout to be disposed behind said other faucet, and a longitudinal valve in said body having an operating handle beyond the forward end of the body and having a passage to establish communication between 25 said inlet portion and spout and a longitudinal channel to establish communication between said inlet portion and nipple, said passage and channel being arranged for the alternate flow from the inlet portion into 30 said spout and nipple.

35 2. A duplex faucet comprising a body having an inlet portion, a delivery spout leading from a point opposite to said inlet portion, a hose attaching nipple extending from the body at a point spaced longitudinally from said inlet portion, and a spigot valve rotatable in said body having a passage to establish communication between 40 said inlet portion and spout and a longitudinal

channel to establish communication between said inlet portion and nipple, said passage and channel being arranged for the alternate flow from said inlet portion to said spout and nipple.

45 3. A duplex faucet comprising a body having an inlet and an outlet, a spigot valve rotatable within the body for establishing and cutting off communication between said inlet and outlet, the valve having a stem extending from one end, a gland member 50 fitted on the stem and engaging the body for retaining the valve therein, said valve having a lug extending therefrom, and a portion in the body in which the valve turns provided with a bayonet slot in which said 55 lug is movable to permit the turning movement of said valve and to permit the removal of the valve in one position when said gland member is removed.

60 4. A faucet comprising a body having an inlet and an outlet, a bushing fitted within the body having ports registering with said inlet and outlet, a spigot valve rotatable in the bushing having means to register with said ports for the flow therethrough, the 65 valve having a stem projecting from one end thereof beyond one end of the bushing and having a lug at one side, said bushing having a bayonet slot extending from said end 70 thereof for the movement of the lug therein to limit the turning movement of the valve, and a gland member engaging the bushing and fitted on said stem for holding the valve within the bushing.

75 In testimony whereof I hereunto affix my signature.

JACOB T. JOHNSON.
